CASEMENT WINDOW ADJUSTER

Hancil Cordrey and Walter J. Duvall,
Chula Vista, Calif.

Application March 25, 1935, Serial No. 12,809

12 Claims. (Cl. 268—119)

The present invention relates to an improved adjuster for operating casement windows and the like.

Heretofore, various types of adjusters have been devised wherein they are capable of swinging the window sash to an open position solely by a right or left movement as the case may be. Other types have been advocated wherein a re-arrangement of the operating parts is necessary to accommodate the swinging in the required direction. In all of said types, the friction which exists between the moving parts has noticeably retarded the easy operation of the sash, and the sagging of the sash and strain upon the various parts has tended to place the assembled parts out of plumb and also to impede and detract from the proper functioning of the various parts. Then too, the slots occurring in the adjuster usually extend completely thru it thus making the device unsightly, and tending to cause it to become inoperative by reason of dust and foreign particles collecting in the slotted portion thereof. Furthermore additional stock has for this reason been required in order to provide adequate strength.

The aims and objects of the present invention are to eliminate these several disadvantages which collectively tend to retard the sales of such devices in the market.

A summary of the objects is: First, to provide in a device of the above character an adjusting arm having a cam groove of an endless character in its underside, to cooperate with a pin adapted to travel in the groove for the purpose of rendering the arm usable with either a right or left hand swinging sash.

Second, to provide a wearing strip on the upper face of the adjusting arm to engage with a supporting flange of a bracket which is fastened to the sash and said supporting bracket having a pin which projects upwardly to engage with the cam groove aforesaid.

Third, to provide an adjusting arm having a cam slot on the underside which may be kept in a lubricated condition and free from dirt and silt.

In the drawing: Fig. 1 is a perspective view showing the invention applied to a casement sash which is shown in its partly opened position.

Fig. 2 is a plan view of the adjuster arm and a portion of the operation mechanism applied thereto.

Fig. 3 is a side elevation of the adjuster arm shown in Fig. 2.

Fig. 4 is a bottom view of the adjuster arm.

Fig. 5 is a perspective view of the sash supporting bracket and operating bracket, and Fig. 6 is a section taken on line 6—6 of Fig. 2.

Referring in detail to the drawing, the invention is shown applied to a window sash 1 fastened by means of a butt 2 to a window stile 3.

The window screen 4 swings inwardly and the sash 1 swings outwardly, that is to say, away from the observer, as viewed in Fig. 1. The hinge mounting for the screen is not shown, but it is preferably located at the same side of the window opening as are the hinges for the sash.

The mechanism 5 for operating the sash is mounted upon the sill 6 between the sash and the screen and is designed in such a manner as to accommodate itself to the minimum distance existing between the sash and the screen at present provided by the building trade. Said mechanism is operated by means of a crank 7 having a shaft or shank portion 7a which is extended thru an opening in the sash of the screen. An escutcheon 8 is secured to the sash of the screen, said escutcheon having thru it an opening 10 which aligns with the opening thru the sash of the screen. The greater portion of the wire part of the screen is broken away in Fig. 1 in order to avoid obscuring the sash operating mechanism.

The sash operating mechanism 5 includes a base plate 11, a cover plate 12, a swingable operating arm 13 journaled between said plates and a worm 14 to move said arm, in combination with a bracket 15 which is attached to the sash. Said plates 11 and 12 may be designed otherwise than illustrated in the drawings, to suit the taste of the manufacturer, the essential thing being that they cooperate to furnish a secure and satisfactory mounting means for the movable parts of the operating mechanism.

As shown in Figs. 1 and 2 of the drawing, the base plate 11 is, at its left end provided with an apertured extension 11a to receive an attaching screw 16. At its other end it underlies the cover plate, these plates having alining apertures to receive screws 17 whereby said plates are secured to each other as well as to the sill.

Between the holes for the screws 17 the plates 11 and 12 are each provided with an aperture into which is closely fitted a dowel pin 12d. In Fig. 2 the aperture 11d in the base plate 11 is shown into which the lower end of the dowel pin 50 snugly fits. This dowel pin has been found, in practice, to be very necessary as a means for properly positioning the plates in order that the worm 14 may be maintained in a proper operative relation to the other moving parts.

The juxtaposed faces of the base plate and cover plate are recessed to house the worm 14 and to provide bearings for its end portions or hubs 18 and 19. The hub 18 is provided axially 5 with a square socket with which a square end portion of the crank cooperates.

The base plate is constructed with an extension 22 and the cover plate with an extension 23. Between said extensions is mounted a segmental 10 gear 24 formed integral with the sash operating arm 13. In the arrangement shown in the drawing, said gear 24 meshes with the worm 14 to swing said arm outwardly when the crank is operated in a clockwise direction, and to swing said 15 arm inwardly when said crank is operated in a counterclockwise direction, but, as will be explained later, the location of the operating mechanism may be reversed with relation to the window opening in order to operate a sash hinged to the 20 opposite side of the window opening.

The gear 24 is held in mesh with the worm by means of a cap screw 25 which is tapped into the extension 22. The operating arm is thus pivoted to swing about the screw as an axis. 25 The two faces of the gear are flat and operate between the extensions with a working fit to cause the arm to remain in the same plane during its swinging movements. This arrangement offsets the tendency of the window to sag.

30 In its under face the arm 13 is provided with a double groove of a continuous character having the two runs or tracks, 26 and 27 which are separated from each other by the rib 28. There is a clearance 29 at one end of this rib to provide 35 a connection between the two runs of the groove. At the opposite end of the rib there is pivotally mounted a pointed switch arm 30, the function of which will presently appear. Beyond said switch arm the two runs of the groove are merged 40 into a short groove extension 31 which aligns with the rib 28.

The bracket 15 carried by the sash 1 comprises a base supporting flange or arm 15a and a side 45 attaching flange 15b which extends at a right angle to said base flange. The attaching flange 15b receives screws 32 whereby the bracket is attached to the sash. As a convenience in assembling the parts, said flange 15a is shown attached to the body portion of the bracket by means of a pair of screws 15c one of which is shown in Fig. 5. In a vertically spaced relation to the base flange 15a the bracket is provided with an upper flange or arm 34 to support the sash if it tends to sag.

50 Directed upwardly from the mid-width of said base flange is a cylindrical shank 33 which, with a working fit, operates in one or the other of the groove runs 26 and 27 to open and close the sash. Said shank 33 may be the stem of a rivet-shaped 55 bolt which is driven friction tight thru an aperture provided therefor in the base flange 15a.

Along the mid-width of the upper face of the operating arm 13 there is preferably a wearing strip 35 to engage with the flange 34 of the bracket 60 to minimize the friction between these parts and to protect the body portion of the arm from an unsightly wearing away.

As illustrated in Fig. 4 the switch member 30 is constructed and arranged in such a manner 65 that, when swung completely to either side it forms a continuation of the adjacent wall of the opposite run of the double groove along which the shank 33 travels, thus directing said shank into the groove extension 31 when the closing 70 movement of the window is completed.

In assembling the parts, the flange 34 of the bracket 15 is disposed transversely to and caused to engage the upper side of the swingable arm 13 and then after the shank 33 has been brought into proper operative relation to the desired run 5 of the double groove the bracket arm 15a is secured to the body portion of the bracket by means of the screw 15c.

When the device is mounted in the relation to the window opening shown in Fig. 1, the run 27 10 of the slot will be traversed in reverse directions by the shank 33 during the opening and closing movements of the window, and the switch member 30 will at all times occupy the full line position of Fig. 4, thus forming a continuous track 15 between the slot run 27 and the slot extension 31. When the device is placed at the other side of the window, the switch member will continuously occupy the dotted line position of Fig. 4 thus conducting the shank 33 from the groove 20 run 26 to the groove extension 31, and vice versa. The pivotal mounting of the switch member 30 should be sufficiently snug to guard against accidental displacement of the switch while the shank occupies the slot extension 31, as is the case when 25 the window is fully open.

We claim:

1. A casement window adjuster comprising an adjuster arm, there being an endless cam groove in the underside of said arm, one half of said groove being utilized to operate the opening and closing of right hand swinging sashes and the other half of said groove being utilized to operate the opening and closing of left hand swinging sashes, in combination with a sash provided with 35 a bracket having a flange which overrides said arm and another flange which underrides said arm, the latter flange having an upstanding pin engageable within said groove.

2. In a casement window adjuster, an adjusting arm having an endless cam groove, in combination with a sash provided with a bracket having a pin engaging said groove, said groove providing two runs, one run being used when the adjuster is applied to right hung sashes and the other run being used when the adjuster is applied to left hung sashes, and a pivoted tongue to maintain said pin in a selected path while said pin is traversing a particular part of said groove. 40

3. In a device of the kind described, in combination, a horizontally swingable sash, a horizontally swingable arm having a double longitudinal groove in its lower face, said groove including two substantially straight parallel runs, means to impart back and forth swinging movements to 50 said arm, a bracket carried by said sash, said bracket having an upstanding shank which is engageable with both runs of said groove with a working fit, and a switch member to change the path of movement of said shank at a point 55 where the two runs of said groove meet, thus adapting the device for reversal from one side of the window opening to the other side thereof.

4. In a device of the kind described, in combination, a window frame including a window 65 stool, a horizontally swingable sash hinged mounted on said frame, a sash operating means fastened to said stool, a bracket carried by said sash and cooperating with said sash operating means whereby the opening and closing of said 70 sash is effected, said means comprising a horizontally swingable arm, and a pair of jaws between which said arm swings in a non-tilting manner, said arm having an endless cam groove in its underside and providing selective paths 75.

whereby the swinging movements of both rights and left hand sashes are effected, and said bracket having a flange which underrides said arm and is provided with an upstanding pin engageable within said groove with a working fit to independently operate said sash as aforesaid; said bracket having another flange over-riding said arm, the underside of which bearing-ly traverses the side of said arm which is opposite said slot to provide an auxiliary support for said sash during the swinging movement thereof.

5 5. In a device of the kind described, the combination with a horizontally swingable sash; of a combination sash supporting and sash operating means including a horizontally swingable arm having an endless cam groove in its under side, a bracket secured to said sash, said bracket having one flange slidably resting on the side of said arm which is opposite said groove whereby said sash is furnished with an auxiliary support during the swinging movements thereof, said bracket having a second flange provided with an upstanding pin engaging said groove with a working fit, and one of said flanges being de-
10 tachable.

15 6. In a casement window adjuster, an adjuster arm having a double groove of a continuous character having two runs or tracks, one half of said groove being used for right hung sashes and the other half being used when the arm is applied to left hung sashes, a rib separating said runs, there being a clearance at one end of said rib to provide a connection between the two runs of said groove, in combination with a sash pro-
20 vided with a bracket having a pin engaging said groove, said pin engaging the end of said rib in a locking manner when said sash is in the fully opened position.

25 7. In a casement window adjuster, an adjuster arm having a double groove of a continuous character having two runs or tracks, a rib separating said runs, there being a clearance at one end of said rib to provide a connection between the two runs of said groove, and a pivotally mounted tongue at the other end of said rib, said double groove at a point beyond said tongue merging into a short groove extension which alines with said rib, in combination with a sash provided with a bracket having a shank engaging said groove, said tongue being constructed and ar-
30 ranged in such a manner that, when swung completely to either side it forms a continuation of the adjacent wall of the opposite run of the double groove along which said shank travels to di-
35 rect said shank into said groove extension, thereby to maintain said shank in a selected path and

making the device adaptable for the swinging of both right and left hand sashes.

40 8. A casement window, and a casement window adjuster for causing the swinging of said casement window in either one of its right or left hand positions of installment, said adjuster having a double groove of an endless character, one half of said groove being used for sashes installed to swing to the right and the other half when the adjuster is applied to sashes installed to swing to the left.

45 9. A sash, a sash operator for said sash, said operator having a double groove forming a path of a continuous character, and means including a pin connectible with the groove of said sash operator in such a manner that when one half of said groove is utilized by said pin the swinging movements of right hung sashes is effected and when the other half of said groove is utilized by said pin the swinging of left hung sashes is effect-
50 ed, and a pivoted tongue to maintain said pin in a selected part of the groove for the respective sash.

55 10. The combination: a casement window sash, a casement window frame including a window stool, for said sash, a sash operator fastener to said stool, and means fastened to said sash and engaging said sash operator whereby to effect the opening and closing movements of said sash, said sash operator having a double groove of a con-
60 tinuous character providing two runs or tracks, one half of said groove being used for operating right hung sashes and the other half being used when said operator is applied to left hung sashes.

65 11. In a device of the kind described, in com-
bination, a horizontally swingable sash, a hori-
zontally swingable arm having a double longitudi-
nal groove in its face, said groove including
two substantially straight parallel runs, means
to impart back and forth swinging movements
to said arm, a bracket carried by said sash, said
bracket having a shank which is engageable with
both runs of said groove with a working fit, and
a switch member to change the path of movement
of said shank at a point where the two runs of
said groove meet, thus adapting the device for
reversal from one side of the window opening
to the other side thereof.

70 12. A sash, a sash operator for said sash, said operator comprising an adjusting arm having an
endless cam groove, and a switchable tongue free-
ly operating to and from a position whereby se-
lective paths are provided by said groove thus
making the device reversible to swing a right hand
sash to the right and a left hand sash to the left.
